**QUATERNARY AMMONIUM-TERTIARY AMINE
OXIDE COMPOSITIONS**

John C. Findlan, Chappaqua, and Ralph P. Sorrentino, Elmhurst, N.Y., and Reginald L. Wakeman, Philadelphia, Pa., assignors to Millmaster Onyx Corporation, New York, N.Y., a corporation of New York
No Drawing. Filed Oct. 21, 1965, Ser. No. 500,282
13 Claims. (Cl. 252—106)

This application is a continuation-in-part of application Serial No. 339,307 filed January 21, 1964, now abandoned.

The present invention has for its object the provision of a composition for simultaneously cleaning, softening and sanitizing fabrics and cleaning and sanitizing walls, floors and other inanimate objects, and which is also capable of cleaning and degerming human skin and other tissues to a very low level by a single scrub application. It is a further object of this invention to provide a composition for use for this purpose which comprises a tertiary amine oxide and a microbiologically active quaternary ammonium salt.

In particular, it is an object of this invention to provide a composition and process for simultaneously cleaning and effectively degerming, and also for deodorizing, human skin and other tissues, such as hair and the like by a single scrub application.

Specifically, it is an object of this invention to provide a composition for simultaneously cleaning and greatly reducing the incidence of microbial flora on human skin and other tissues for the purpose of antisepsis.

It is most particularly an object of this invention to very significantly reduce the microbial population on the skin upon the very first scrub application, rather than as a result of continued use over a prolonged period.

Other objects of this invention will become apparent from the following description.

Certain quaternary ammonium salts are well known and widely used because of their microbiological activity. Such compounds have in common a long alkyl radical containing from 8 to 20 carbon atoms attached either directly or indirectly through a benzyl group or a phenoxyethoxyethyl group to the nitrogen atom of the quaternary ammonium compound. They will be defined in greater detail hereinafter.

Such quaternary ammonium compounds exhibit, however, certain drawbacks in that they are chemically and microbiologically incompatible with anionic surface active agents, that is to say, when combined in solution with anionic surfactants they are precipitated and/or deactivated microbiologically. Non-ionic detergents of the ethylene oxide adduct type are utilized in combination with quaternary ammonium germicides in various commercially available detergent sanitizers, but such detergent sanitizers all suffer from rather serious restrictions in the permissible ratio of non-ionic detergent to quaternary ammonium compound. The customary ratio of these two components is usually in the order of 1.5:1. If this value is exceeded, the germicidal activity of the quaternary ammonium compound is impaired until at high ratios such, for example, as 3 or above, the microbiological activity of the quaternary ammonium compound is completely vitiated. Inasmuch as the use concentration of quaternary ammonium compound is normally between 400 to 600 parts per million, the aforementioned limitation with respect to the permissible amount of non-ionic places a severe restriction on the amount of non-ionic detergent which can be utilized in such detergent sanitizers at use dilutions, thus making these materials unsuitable for adequate cleaning.

Furthermore, although amphoteric detergents have

2

been combined with quaternary ammonium compounds, such combinations are particularly effective on the acid side under which condition the amphoteric material exists in the form of a cationic surfactant. Under alkaline conditions, the amphoteric being in the nature of an anionic surfactant is incompatible with quaternary ammonium germicides.

Hence, it will be apparent that there is a vital need for a satisfactory composition which will both clean and sanitize under wide conditions of acidity and alkalinity and throughout wide ratios of detergent to sanitizer.

We have found that quaternary ammonium compounds can be combined with tertiary amine oxides of the type hereinafter set forth over a wide range of pH and throughout a wide range of ratios of one component to another without any deleterious effect on the microbiological activity of the quaternary ammonium compound. Amine oxides of the alkyl dimethyl amine oxide family in which the alkyl radical contains from 8 to 20 carbon atoms have been described in USP 2,169,976 and until recently have been considered to be cationic in nature. We have found, however, that these materials are not truly cationic and that, contrary to certain assumptions made in the literature without experimental evidence, these amine oxides of themselves possess no germicidal activity. We have found, for example, that lauryl dimethyl amine oxide, myristyl dimethyl amine oxide, cetyl dimethyl amine oxide, stearyl dimethyl amine oxide and oleyl dimethyl amine oxide of themselves all possess no microbiological activity measurable as phenol coefficient by the standard method described in the "Official Methods of Analysis of the Association of Official Agricultural Chemists," Ninth Edition (1960), page 63 et seq. When run against *Staphylococcus aureus* and *Salmonella typhosa*, none of these compounds just listed exhibited any appreciable phenol coefficient.

It has moreover, recently been found that amine oxides of the alkyl dimethyl amine oxide class are compatible with many anionic detergents. Hence, it is surprising that these materials are both physically and microbiologically completely compatible in all proportions and under all conditions of pH with quaternary ammonium compounds.

Up to the present time, there has been no satisfactory method for washing, softening, and sanitizing fabrics in a single operation. It has been necessary to conduct these operations singly or, at best, in at least two different operations because of the incompatibility of the customary anionic detergents and fabric softeners which are cationic in nature. Moreover, the satisfactory sanitization of fabrics, especially diapers, requires the use of cationic germicides which are also incompatible with anionic detergents so that there is precipitation in the bath when they and anionics are used together, with resultant bacteriological inactivation of the solution. Moreover, compatibility problems, especially microbiological in nature, arise as hereinabove described when a non-ionic is used as the sole detergent in combination with relatively small amounts of quaternary ammonium germicides.

The compositions comprising said tertiary amine oxides and said microbiologically active quaternary ammonium salts may also be used as surgical scrub soaps of exceptional effectiveness by a single use. They may also be employed in shampoos for the control of dandruff; or as deodorant soaps; or as detergents for any condition wherein it is desired to reduce or control the bacterial or fungal population of the skin or related tissue.

In addition to pre-operative scrubbing, these compositions are of value in many other fields where the bacterial count of an individual's skin should or must be kept low, for example in food handling in such fields among others as meat-packing, egg-breaking and the like; in nursing, and particularly in baby nursing; by mechan-

ics and others who are subject to cuts, abrasions and other skin injuries which are likely to result in infection; for such cosmetic conditions as acne or boils; and in general wherever it is desirable to employ a degerming washing medium to reduce the incidence or prevent the transmission of infection in, on, to or from the skin or related tissue.

In addition to the cleansing and sanitizing effects of the compositions of this invention, there also obtains the well-known emollient effect upon the skin which is characteristic of the tertiary amine oxides which are employed as components of these compositions. Since the said compositions are effective over a wide pH range, they may be employed in the normal, slightly acid range of the skin. This is a marked contrast to the harsh effect upon tissues of strong or alkaline soaps and of synthetic detergents which effectively remove the natural lubricant oils of those tissues.

The amine oxides which we employ according to the present invention are alkyl dimethyl amine oxides in which the alkyl radical contains from 8 to 20 carbon atoms and correspond to the general formula

25

where R contains from 8 to 20 carbon atoms and may, if desired, be unsaturated in nature, where R' and R'' may be methyl, ethyl, propyl, isopropyl, hydroxyethyl, hydroxyethoxyethyl, or hydroxyethyl polyethoxyethyl radicals and wherein the oxygen is linked to nitrogen by means of a semi-polar bond. If desired, R' and R'' may jointly constitute the $-\text{CH}_2-\text{CH}_2-\text{O}-\text{CH}_2-\text{CH}_2-$ radical, i.e. 35 the above formula is:

40

While all of these amine oxides have deteritive power, those containing fourteen carbon atoms, or less, are also 45 good foaming agents whereas those possessing 16 carbon atoms, or more, are poor foaming agents.

As suitable quaternary ammonium compounds which we may use in the compositions of this invention, we may employ any water-soluble quaternary ammonium salt having a long alkyl radical containing from 8 to 22 carbon atoms attached either directly to the nitrogen atom or through an intermediate benzyl or phenoxyethoxyethyl radical and having a phenol coefficient of at least 100 with respect to the *Staphylococcus aureus* and *Salmonella typhosa* at 20° C. when determined by the standard method given in the "Official Method of Analysis of the Association of Official Agricultural Chemists," Ninth Edition (1960), page 63 et seq. Typical examples of these quaternary ammonium compounds are alkyl trimethyl ammonium chlorides, alkyl-benzyl trimethyl ammonium chlorides, alkyl dimethyl benzyl ammonium chlorides, alkyl dimethyl menaphthyl ammonium chlorides, alkyl dimethyl substituted-benzyl ammonium chlorides in which the benzyl radical is substituted with one or more side chains containing from 1 to 5 carbon atoms such, for example, as methyl, dimethyl, ethyl, isopropyl, tert-butyl, n-amyl, isoamyl, tetramethyl, trimethyl and the like in which the carbon atoms may all be in the same or different side chains or in which the benzyl radical may be substituted by an alkylene group such as tetrahydro menaphthyl or in which the benzyl radical bears one, two or more halogen atoms such as chlorine or bromine, alkyl pyridinium chlorides, alkyl isoquinolinium chlorides and bromides, alkyl lower-alkyl pyrrolidinium chlo-

rides, alkyl lower-alkyl morpholinium chlorides in all of which the alkyl group may have from 8 to 22 carbon atoms and the lower-alkyl group may have from 1 to 4 carbon atoms and alkyl phenoxyethoxyethyl dimethylbenzyl ammonium chloride in which the alkyl radical may be iso-octyl or nonyl and in which the benzyl radical may, if desired, be substituted by a methyl radical. Various other analogs of these quaternaries may also be employed such, for example, as cetyl dimethyl ethyl ammonium bromide or oleyl dimethyl ethyl ammonium bromide. Instead of the foregoing chlorides, we may also employ the corresponding bromides, methosulfates, ethosulfates or other water-soluble analogs. We may also employ mixtures of two or more of the foregoing quaternary ammonium compounds. In particular, we prefer to employ a mixture of alkyl dimethyl benzyl ammonium chloride in which the alkyl radical blend contains at least 50% myristyl, together with alkyl dimethyl ethyl-benzyl ammonium chloride in which the alkyl radical blend is predominantly (at least 50%) C₁₂, this blend being employed in approximately 1:1 ratio by weight.

We prefer to use the quaternary ammonium compounds which have phenol coefficients of more than 500 against *Staphylococcus aureus*; such for example are BTC-824, an alkyl dimethyl benzyl ammonium chloride in which alkyl is 60% C₁₄, 30% C₁₆, 5% C₁₂ and 5% C₁₈; Tetrosan 3,4 D, an alkyl dimethyl dichlorobenzyl ammonium chloride in which the alkyl is 50% C₁₂, 30% C₁₄, 17% C₁₆ and 8% C₁₈; BTC-471 and BTC-927, which are, respectively, alkyl dimethyl ethyl-benzyl and alkyl dimethyl dimethylbenzyl ammonium chlorides in which the alkyl distribution is the same as in Tetrosan 3,4 D; lauryl dimethyl menaphthyl or tetrahydromenaphthyl ammonium chloride; lauryl isoquinolinium bromide and the like; or mixtures thereof. The aforesaid products are sold by Oynx Chemical Corporation under the previously mentioned trademark designations.

The compositions of this invention are preferably prepared as liquids for convenient use as a surgical or other degerming scrub soap. However, if desired they may be thickened by certain additives into a gel or a paste or to be molded into a bar by methods well known to the art; or they may be prepared as a powder, as for example as an adduct with urea, by mixing the composition with crystalline urea in sufficient amounts to produce a free-flowing powder.

When used for cleaning inanimate objects, they may contain other appropriate adjuvants such, for example, as alkaline builders including the various phosphates such as trisodium phosphate, tetrasodium pyrophosphate, tetra-potassium pyrophosphate, sodium tripolyphosphate, borax, sodium silicate, sodium carbonate, sodium bicarbonate, sodium sulfate and the like.

In addition to cleaning fabrics, they may be used, for example, in scrub soaps, for cleaning floors and walls of hospitals; they may be used in dairy sanitation; they may be used as detergent sanitizers in bars and restaurants and have general janitorial maintenance purposes.

They may also be used in a wide variety of detergents destined for home use such, for example, as in dish-washing compounds and in detergents for both heavy and light duty laundry operations. Such compositions may also be employed for various cosmetic uses, particularly for hair shampoos by means of which the hair is not only cleansed but also left in a static-free, smooth and glossy condition.

The anti-bacterial effectiveness of deodorant toilet bars as well as liquid antiseptic or germicidal hand scrubs is predominately based on the principle that the active agent gradually builds up on the skin after repeated use, resulting in a lowering of the bacterial flora. Bacterial counts of the wash waters from successive washings are used as an indirect measure of the bacteria existing on the skin. Many techniques have been proposed for the *in vivo* evaluation of skin antisepsis, most of them based

upon the Price multiple basin technique. (P. B. Price, Journal of the American Medical Association, 3 (22), pp. 1993-96, November 26, 1938). The Cade modification of the Price method is quite frequently used; briefly, it consists of determining an initial count in a series of five washes; after 5, 11, and 12 days use of the test soap, additional counts are made to follow the course of the reduction of bacteria on the skin. (A. R. Cade, Soap and Sanitary Chemicals, 26, pp. 35-38, 73, July 1950.)

A split-glove technique proposed by Quinn serves to considerably shorten the above techniques and has the distinct advantage that each subject serves as his own control. (H. Quinn et al., Applied Microbiology, 2, pp. 202-4, 1954.) In brief, the subject has one hand covered with a glove and washes the other with the control soap. After rinsing in the basin, the glove is removed, a fresh one is placed on the other hand, and the procedure is repeated with the test soap, in another basin.

In all of these methods, following accurate time intervals for lathering and rinsing and performing each successive wash in a separate basin, the bacterial counts should show a definite decrease with each succeeding wash. The first basin generally shows a high count which consists of transient bacteria, the amount and types of which may vary due to environmental conditions. The bacteria removed with succeeding washes were described by Price as resident bacteria, capable of thriving on skin or whose normal habitat can be considered to be skin. The word "degermation" is used to designate reduction in these tests of the total number of bacteria present, irrespective of whether the organisms are or are not pathogenic.

to be gained is that any given isolated application will immediately provide the desired result. Whether used by workers in a food handling plant or by a surgeon or a dentist, the first wash will significantly reduce the bacterial flora on the skin—not only the transient, but also the resident bacteria.

In practice, it is virtually impossible to expect the continued and uninterrupted use by an individual of any single agent whose activity depends upon just such process. It is also a fact that alcohol or ordinary soap or detergents can completely remove any residual film of such antiseptic agent. The advantages of the product of this invention are therefore evident.

While not limited thereto, the invention will be apparent from the following illustrative examples:

Example I

A 30% viscous solution of stearyl dimethyl amine oxide was combined with varying amounts of a 50% active solution of alkyl dimethyl benzyl ammonium chloride in which the alkyl distribution corresponded to 60% C₁₄, 30% C₁₆, 5% C₁₂, 5% C₁₈ and an equal amount of alkyl dimethyl ethylbenzyl ammonium chloride in which the alkyl distribution corresponded to 50% C₁₂, 30% C₁₄; 17% C₁₆, 3% C₁₈. The ratios were adjusted so that the proportion of amine oxide to quaternary ammonium germicide on a 100% active basis ranged from about 50:1 to about 5:1 and the pH's of the solutions on an as is basis all varied from 4.0 to 11.0.

The composition of the preparations in the following and subsequent examples is given in parts by weight:

TABLE I

	A	B	C	D	E	F	G	H	I
Composition:									
Staryl dimethyl amine oxide, 30%	40.0	40.0	40.0	34.0	34.0	34.0	17.0	17.0	17.0
Alkyl ¹ dimethyl benzyl ammonium chloride, 50%	0.25	0.25	0.25	1.0	1.0	1.0	1.0	1.0	1.0
Alkyl ² dimethyl ethyl-benzyl ammonium chloride, 50%	0.25	0.25	0.25	1.0	1.0	1.0	1.0	1.0	1.0
Water				Balance					
pH	11.0	7.0	4.0	11.0	7.0	4.0	11.0	7.0	4.0

¹ Alkyl distribution: 60% C₁₄, 30% C₁₆, 5% C₁₂, 5% C₁₈.

² Alkyl distribution: 50% C₁₂, 30% C₁₄, 17% C₁₆, 3% C₁₈.

Hexachlorophene, trichlorocarbanilides, and bromo salicylanilides which are in widespread use all depend on repeated and constant use for lowering bacterial flora on the skin. Products based on these materials state this very fact in their literature. The "Phisohex" (trademark, Winthrop Laboratories, New York, N.Y., Brochure 5828, July 1963) brochure indicates that "cumulative and germ-controlling properties are maintained with the constant and exclusive use" of the product, which is a sudsing emulsion containing entsufon, lanolin cholesterol, petrolatum and 3% hexachlorophene, otherwise 2,2' methylenebis (3,4,6 trichlorophenol). The manufacturer states that "patients scheduled to undergo elective surgery should wash the operative site daily for 5-10 days before operation." The "Septisol" (trademark, Vestal Laboratories, St. Louis, Missouri, of which the active ingredients comprise 0.75% of hexachlorophene and 2% of anhydrous soap) label indicates that the product "is not intended for antiseptic use by a single application. Regular dialy use is essential to obtain maximum bacterial reduction."

The product of this invention is based on the concept that antiseptic preparation should reduce the bacterial population on the very first application, and not depend on repeated use for its activity. The considerable advantage

Killing dilutions were run on the preceding compositions by the method given in the "Official Methods of Analysis of the Association of Official Agricultural Chemists," Ninth Edition (1960), page 63 et seq., using as test organisms both *Staphylococcus aureus* and *Salmonella typhosa*. Killing dilutions against these organisms were found to be as great or greater than the corresponding killing dilutions of the quaternary by itself.

Example II

In a manner similar to that shown in Example I, 1 part of a 50% active solution of the blend of quaternary ammonium germicides described in Example I was combined with 5 parts, 10 parts and 50 parts respectively of a 30% active amine oxide mixture containing approximately 60% myristyl dimethyl amine oxide and 40% cetyl dimethyl amine oxide. Each of these three compositions was again divided into three parts and the pH adjusted to 4, 7 and 11 respectively using hydrochloric acid or sodium hydroxide to obtain the appropriate levels.

Killing dilutions were run on these compositions with the same results as described in Example I.

Example III

	Parts
Cetyl dimethyl amine oxide, 30%	5.0
N-lauryl N-methyl glycine, 30%	12.0
Alkyl ¹ dimethyl benzyl ammonium chloride, 50%	0.5
Alkyl ² dimethyl ethyl-benzyl ammonium chloride, 50%	0.5
Water	Balance

¹ Alkyl distribution: 60% C₁₄, 30% C₁₆, 5% C₁₂, 5% C₁₈.
² Alkyl distribution: 50% C₂, 30% C₁₄, 17% C₁₂, 3% C₁₈.

The preceding composition was adjusted to a pH of 6.0 to give a non-irritating, effective surgical scrub having a pleasing slip and emollient effect on the hands. Microbiological evaluation showed it to have essentially the same killing dilutions with respect to *Staphylococcus aureus* and *Salmonella typhosa* as the corresponding 1% solution of the same blend of quaternary ammonium salts alone, i.e. 1/50,000 and 1/40,000 respectively, on a 100% active basis.

Example IV

Lauryl dimethyl amine oxide, 30 %	35.0
Stearyl dimethyl amine oxide, 30 %	9.0
Quaternary ammonium germicide blend of equal amounts of the alkyl dimethyl benzyl ammonium chloride and alkyl dimethyl ethyl-benzyl ammonium chloride of Example III, 50%	1.0
Hydroxyethyl cellulose	0.5
Acetylated lanolin	0.5
Water to make 100.0.	

This was adjusted to a pH of 6.0 to give a non-irritating surgical scrub having a pleasing slip and emollient effect on the hands.

Example V

The degerming product of Example IV was tested by a modification of the Quinn split-glove technique cited

above. Ivory soap was used as a control. The test was carried out as follows:

1500 cc. of tap water was charged into a sterilized basin (basin #1). 1 and 2 cc. portions were removed for plating (correction for blank). 500 cc. of Azolectin (lecithin) and Tween 80 (polyoxyethylene sorbitan monoleate) neutralizer were added to the basin to inactivate the quaternary. A sterile surgical glove was placed on one hand and both hands were then moistened in the basin. Both hands were raised above water level and cupped together and 2.0 cc. of the composition of Example IV was poured on the hands. The subject then began to work up a lather and scrubbed the ungloved hand with a sterile brush for 2½ minutes. The subject rinsed for 15 seconds and the hands were allowed to drip over the basin. The procedure was repeated again with 2.0 cc. of the degerming composition of Example IV for 2½ minutes followed by 15 seconds rinsing which concludes basin #1. The brush was left in the basin and allowed to set for 30 seconds to one minute before plating.

Thereafter the hands were rinsed three times as follows:

Basin #2, #3, and #4 each received 2000 cc. of tap water in sequence and were used to wash in the same manner as basin #1, except that the test hand used Ivory Soap (8% aqueous sterile solution) and no neutralizer. At the conclusion, the glove was removed, a fresh one placed on the opposite hand, and the entire procedure repeated exclusively with Ivory Soap solution.

1 cc. from each wash was plated in duplicate into Tryptone Glucose Extract Agar. Subsequent dilutions from each basin were made as deemed necessary so as to obtain good countable plates. The standard plate count method was followed in each case.

Similarly, a commercially available hexachlorophene detergent sanitizer ("Phisohex"), with Ivory Soap as a control as before. A new panel of subjects was employed.

The following tables indicate the number of organisms counted in a culture of 1 cc. of the wash water in each case, and also the percentage reduction per basin as compared with the control.

TABLE II
Test preparation: Degerming composition of Example IV.
Control: Ivory soap.

The above data show that the very first scrubbing with the products of this invention results in a great diminution of the bacterial count in the washings amounting to more than 95%; and that subsequent washings with an ordinary soap continue to show further diminution as compared with the use of soap alone. It will thus be apparent that a single application as a surgical scrub is remarkably effective in degerming the hands by an extremely high percentage.

When the widely used hexachlorophene type of degerming detergent is used, however, the count after the scrubbing is of a greater order of magnitude, and further washings with soap causes no further diminution in the count as compared with soap alone throughout; in fact, ordinary soap appears superior as a degerming agent in the second, third and fourth washings, simply by force of mechanically removing some of the residual viable organisms.

The products of this invention thus surprisingly effect the said very considerable reduction in the skin microbial level on the first application, and they do not depend upon continued or repeated use for their activity. This is in marked contrast with the commonly used surgical scrubs which specifically call for repeated use in order to build up the degerming effect, which effect may be cancelled out by the subsequent use of ordinary detergents such as soap, or by washing with solvents such as alcohol.

Example VI

	Parts	60
Cetyl dimethyl amine oxide, 30%	10.00	
N-lauryl N-methyl glycine	30.00	
Lauryl isoquinolinium bromide, 75%	0.25	
Water	Balance	

This composition was adjusted to a pH of 5.0 with hydroxy acetic acid. It showed good foaming and excellent slip. Its lauryl isoquinolinium bromide content exhibits excellent microbiological activity versus *Pityrosporum ovale*; i.e. its killing dilution versus a red strain of this organism was 1/45,000. Hence this product is suitable as a dandruff shampoo.

As suitable additional softeners for use in compositions of this invention in addition to the amine oxides themselves, we may employ any of the cationic softeners available for use in so-called "home laundry softeners" such,

for example, as distearyl dimethyl ammonium chloride or methosulfate, distearyl methyl polyethoxyethyl ammonium chloride or methosulfate or the corresponding quaternary ammonium salts in which the two long alkyl radicals are mixtures of the fatty radicals present in the alcohols obtained by hydrogenation of tallow. We may also use the corresponding dialkyl quaternary ammonium chlorides or methosulfates in which the alkyl radicals are largely cetyl, myristyl or lauryl. We prefer to use quaternaries of the aforementioned types in which the two alkyl radicals are derived from hydrogenated tallow. Other softeners suitable for incorporation in our composition include the well-known imidazoline types long used by textile mills as permanent softeners such, for example, as those prepared by condensation of approximately one mole of stearic acid with one mole of diethylene triamine or of hydroxyethyl ethylene diamine with the elimination of sufficient water during reaction to form, in large part, an imidazoline ring having, for example the following structure:

and in which compounds quaternization of at least one of the nitrogen atoms is effected with acetic anhydride, diethyl sulfate, triethyl phosphate or phosphite or the like. The preparation of various compounds of this nature is described in U.S.P. 2,200,815. Other softeners of similar nature are obtainable by reaction of about one mole of imidazoline derived from the condensation of stearic acid with a mole of diethylene triamine and subsequent reaction of the product with urea, under heat, whereby ammonia is eliminated and a complex urea derivative of the imidazoline is formed which may subsequently be dissolved in acid or quaternized with dimethyl sulfate, diethyl sulfate, triethyl phosphate or phosphite, acetic anhydride, benzyl chloride and the like. The preparation of such products is described in U.S.P. 2,304,369.

11

A powdered detergent-softener-sanitizer is illustrated as follows:

Example VII

	Parts
(1) Stearyl dimethyl amine oxide, 30% active	15.0
(2) Alkyl ¹ dimethyl benzyl ammonium chloride blended 1:1 by weight with alkyl ² dimethyl ethyl-benzyl ammonium chloride, in the form of a powder containing 40% active quaternary ammonium salt content deposited on urea	0.5
(3) Dialkyl ³ dimethyl ammonium methosulfate, in the form of a powder containing 40% active cationic softener content deposited on urea	2.5
(4) Sodium tripolyphosphate	59.0
(5) Sodium metasilicate pentahydrate ⁴	10.0
(6) Sodium acid pyrophosphate	13.0

¹ Alkyl distribution: 60% C₁₄, 30% C₁₆, 5% C₁₂, 5% C₁₈.

² Alkyl distribution: 50% C₁₂, 30% C₁₄, 17% C₁₆, 3% C₁₈.

³ The alkyl radicals being those derived by hydrogenation of tallow.

⁴ "Metso" Granular, sold by Philadelphia Quartz Company.

The powders of the above formulation, i.e. items 2 through 6, were charged into a clean stainless steel sigma-blade mixer capable of being steam heated and the temperature of the contents was raised to about 40° C. while being thoroughly mixed.

In a separate vessel, the stearyl dimethyl amine oxide was diluted with about an equal volume of methanol with warming. This solution was then slowly added to the blended powders while mixing was continued.

The wet slurry thus formed was heated to 85-90° C. with mixing in order to volatilize the alcohol and the water content of the amine oxide.

Mixing with heating was continued until the mass became hard and brittle, breaking up into a powder under the action of the sigma blades. The powder was allowed to dry in the air in pans and then comminuted, being passed through a 200 mesh screen.

We claim:

1. A germicidal agent consisting essentially of (1) at least one tertiary amine oxide of the formula:

wherein R is a member of the group consisting of alkyl and alkenyl having 8 to 20 carbon atoms, and wherein R' and R'' are selected from the group consisting of methyl, ethyl, propyl, isopropyl, hydroxyalkyl, hydroxyalkoxyalkyl, hydroxyalkyl polyalkoxyalkyl, and morpholine containing R', R'' and N as members, the alkyl, the hydroxyalkyl compounds being lower alkyl, and (2) at least one germicidal quaternary ammonium compound having at least one long chain alkyl group of 8 to 22 carbon atoms attached to the quaternary nitrogen and having a phenol coefficient of at least 100 with respect to *Staphylococcus aureus* and *Salmonella typhosa* at 20° C., the amine oxide and quaternary ammonium compound being present in the proportion of about 50:1 to about 5:1 parts by weight.

2. The composition of claim 1 wherein the amine oxide is stearyl dimethyl amine oxide and the quaternary ammonium compound is alkyl dimethyl benzyl ammonium chloride wherein the alkyl has 12 to 18 carbon atoms.

3. The composition of claim 1 wherein the amine oxide is cetyl dimethyl amine oxide, the quaternary ammonium compound is lauryl isoquinolinium bromide and wherein N-lauryl N-methyl glycine is present in an amount of about three times that of the amine oxide.

4. The composition of claim 1 wherein the amine oxide is stearyl dimethyl amine oxide and the quaternary ammonium compound is a mixture of alkyl dimethyl benzyl ammonium chloride and alkyl dimethyl ethyl-benzyl ammonium chloride wherein the alkyls each contain from 12 to 18 carbon atoms.

5. The composition of claim 1 wherein the amine oxide is a mixture of myristyl dimethyl amine oxide and cetyl dimethyl amine oxide, and the quaternary ammonium

12

compound is a mixture of alkyl dimethyl benzyl ammonium chloride and alkyl dimethyl ethyl-benzyl ammonium chloride wherein the alkyls each contain from 12 to 18 carbon atoms.

6. The composition of claim 1 wherein the amine oxide is a mixture of lauryl dimethyl amine oxide and stearyl dimethyl amine oxide, the quaternary ammonium compound is a mixture of alkyl dimethyl benzyl ammonium chloride and alkyl dimethyl ethyl-benzyl ammonium chloride wherein the alkyls each have 12 to 18 carbon atoms, and wherein the composition also includes hydroxyethyl cellulose and acetylated lanolin, each in an amount of about one-half that of the quaternary ammonium compound mixture.

7. The composition of claim 1 wherein the pH is from 4.0 to 11.0.

8. The composition of claim 1 including a cellulose softener agent selected from the group consisting of di higher alkyl dimethyl ammonium halides and methosulfates and higher alkyl imidazolines, said higher alkyls having 11 to 18 carbon atoms.

9. A method of simultaneously cleaning and sterilizing human tissue which comprises applying to said tissue a composition consisting essentially of (1) at least one tertiary amine oxide of the formula:

wherein R is a member of the group consisting of alkyl and alkenyl having 8 to 20 carbon atoms, and wherein R' and R'' are selected from the group consisting of methyl, ethyl, propyl, isopropyl, hydroxyalkyl, hydroxyalkoxyalkyl, hydroxyalkyl polyalkoxyalkyl, and morpholine containing R', R'' and N as members, the alkyl of the hydroxyalkyl compounds being lower alkyl, and (2) at least one germicidal quaternary ammonium compound having at least one long chain alkyl group of 8 to 22 carbon atoms attached to the quaternary nitrogen and having a phenol coefficient of at least 100 with respect to *Staphylococcus aureus* and *Salmonella typhosa* at 20° C., the amine oxide and quaternary ammonium compound being present in the proportion of about 50:1 to about 5:1 parts by weight.

10. The method of claim 9 wherein said composition consists essentially of stearyl dimethyl amine oxide, alkyl dimethyl benzyl ammonium chloride in which the alkyl distribution corresponds to 60% C₁₄, 30% C₁₆, 5% C₁₂ and 5% C₁₈, and alkyl dimethyl ethyl-benzyl ammonium chloride in which the alkyl distribution corresponds to 50% C₁₂, 30% C₁₄, 17% C₁₆ and 3% C₁₈, the components being present in sufficient amounts to establish germicidal effectiveness.

11. The method of claim 9 wherein said composition consists essentially of myristyl dimethyl amine oxide, cetyl dimethyl amine oxide, alkyl dimethyl benzyl ammonium chloride in which the alkyl distribution corresponds to 60% C₁₄, 30% C₁₆, 5% C₁₂ and 5% C₁₈, and alkyl dimethyl ethyl-benzyl ammonium chloride in which the alkyl distribution corresponds to 50% C₁₂, 30% C₁₄, 17% C₁₆ and 3% C₁₈, the components being present in sufficient amounts to establish germicidal effectiveness.

12. The method of claim 8 wherein said composition consists essentially of cetyl dimethyl amine oxide, alkyl dimethyl benzyl ammonium chloride wherein the alkyl group has 8 to 20 carbon atoms, alkyl dimethyl ethyl-benzyl ammonium chloride wherein the alkyl group has 8 to 20 carbon atoms, and, additionally, N-lauryl-N-methyl glycine in about three times the amount of the amine oxide and having a pH of 6.0, the components being present in sufficient amounts to establish germicidal effectiveness.

13. The method of claim 9 wherein said composition consists essentially of lauryl dimethyl amine oxide, stearyl dimethyl amine oxide, alkyl dimethyl benzyl ammonium chloride wherein the alkyl group has 8 to 20 carbon atoms, alkyl dimethyl ethyl-benzyl ammonium chloride where

13

the alkyl group has 8 to 20 carbon atoms, and, additionally hydroxyethyl cellulose and acetylated lanolin, each in about one-half the amount of the total amount of quaternary ammonium compounds, the components being present in sufficient amounts to establish germicidal effectiveness.
